UNITED STATES PATENT OFFICE.

RUDOLPH F. KLOPP, OF THERMOPOLIS, WYOMING.

FALSE BOTTOM FOR WASHTUBS AND THE LIKE.

1,116,711.

Specification of Letters Patent. Patented Nov. 10, 1914.

Application filed October 3, 1913. Serial No. 793,196.

To all whom it may concern:

Be it known that I, RUDOLPH F. KLOPP, a subject of the German Empire, residing at Thermopolis, in the county of Hot Springs 5 and State of Wyoming, have invented certain new and useful Improvements in False Bottoms for Washtubs and the like, of which the following is a specification.

The present invention relates to a false 10 bottom for wash tubs and the like, and has for its object to provide a device of this character which embodies novel features of construction whereby an effective frictional contact with the clothes is obtained and also 15 whereby the water may be heated under the false bottom so as to maintain the same at the proper temperature.

A further object of the invention is to provide a false bottom for wash tubs which 20 is not only constructed to remove the dirt from the clothes by friction, but also to strain the dirt from the upper part of the wash tub or vessel to the bottom thereof so as to keep the water and suds in said upper 25 part of the tub in a clean condition.

With these and other objects in view, the invention consists in certain novel combinations and arrangements of the parts as will 30 more fully appear as the description proceeds, the novel features thereof being pointed out in the appended claims.

For a full understanding of the invention, reference is to be had to the following description and accompanying drawings, in 35 which:—

Figure 1 is a plan view of a false bottom constructed in accordance with the invention, showing the same as arranged within an ordinary wash tub. Fig. 2 is a transverse 40 sectional view on the line 2—2 of Fig. 1. Fig. 3 is a sectional view on the line 3—3 of Fig. 1, and Fig. 4 is a transverse sectional view through a modified form of the invention, showing the same as fitted within an 45 ordinary wash tub.

Corresponding and like parts are referred to in the following description and indicated in all the views of the drawing by the same reference characters.

50 Referring to the drawings, the reference character A designates the false bottom in its entirety, the said false bottom being adapted to be removably placed in a wash tub, washing machine or the like so as to rest 55 loosely upon the bottom thereof. In the present instance the false bottom is shown

for the purpose of illustration as fitted within a wash tub 1. The bottom A, as shown by Figs. 1 and 2, is preferably made in two substantially semicircular sections 2—2 60 which are loosely connected in some suitable manner as by means of the hinged links 3 so as to be readily folded upon each other when it is desired to collapse the false bottom. Washing machines are frequently made with 65 a contracted top, although where the false bottom is constructed in two hinged sections, as above indicated, no difficulty is encountered in placing the same in position within the interior of the washing machine. 70

The false bottom A may be made from sheet metal or heavy glass, the adjacent edges of the two sections 2—2 thereof being loosely connected by the link members 3. In the present instance the extremities of the 75 link members 3 are rolled to provide small sleeves which receive the rods or wires 3^a, the said wires or rods being similarly engaged at intermediate points between the links by corresponding sleeve members 3^b 80 upon the sections 2. This construction admits of the two sections 2—2 being readily folded when such becomes desirable.

Each of the sections 2 of the false bottom is provided with a plurality of independent 85 sets of corrugations running at angles to each other. In the present instance each half 2 of the false bottom is divided into two segmental sections each of which is provided with a set of corrugations 4, the corrugations of each set being parallel to each other and to the radius passing through the middle of the segmental section. It will thus be obvious that the various sets of corrugations 4 extend in different directions so that 95 the clothes will be effectively acted upon to remove the dirt therefrom, regardless of the direction in which they are moved over the bottom. Each set of the corrugations is provided with the longitudinal slots 4^a in the 100 valleys or depressions between the independent corrugations, and with the perforations 4^b which extend in series along the ridges or raised portions of the corrugations. Provision is thus made for carrying the dirt 105 under the bottom as quickly as it is loosened so as to always keep the suds and water above the false bottom as clean as possible.

The false bottom A is provided with a downwardly projecting peripheral rim 5 110 which elevates the false bottom above the bottom of the tub. A water space is thus

provided between the false bottom A and the bottom of the wash tub 1, and the dirt removed from the clothes by friction with the false bottom will pass through the slots 4^a and perforations 4^b and thus be carried away from the clothes.

The invention also contemplates the provision of means for heating the water to maintain the same at the proper temperature. For this purpose a heating coil 7 is arranged under and carried by the false bottom A, the said heating coil being secured to the false bottom by suitable clips 8, and maintained out of electrical contact there-with by the insulation 9. The terminals 10 of the heating coil 7 extend to a suitable plug 11, and electric current may be supplied to the heating coil from any suitable source.

20 As indicated by Fig. 2, the heating coil 7 is formed in complementary sections which are rigidly and permanently applied to the sections 2—2 of the bottom, the adjacent ends of the complementary sections being connected by coiled portions 7^a of insulated wire. These coiled portions 7^a are adapted to be elongated when the false bottom is collapsed and contracted when the false bottom is extended or inverted for use. Provision is thus made for the folding of the false bottom A, although the operative sections of the heating coil 7 are maintained in a spaced position from the false bottom and out of electrical contact therewith.

35 A modification is shown by Fig. 4, in which the false bottom A is constructed in one integral section, and is provided at the periphery thereof with the upwardly projecting flange or sides 12. This flange 12 may be of any desired height, and is formed with several sets of corrugations 13, corre-

sponding to the sets of corrugations 4 of the bottom, and extending at different angles to each other. As the clothes are agitated and brought into contact with the corrugations 13 of the side flanges 12, the said corrugations 13 will coöperate with the corrugations 4 of the bottom to act frictionally upon the clothes and remove the dirt therefrom.

Having thus described the invention, what I claim as new and desire to secure by Letters Patent, is:—

1. A false bottom for wash tubs and the like, including a removable bottom plate subdivided into segmental sections which radiate from a common center, each section being formed with an independent set of parallel corrugations which are disposed at an angle to the corrugations of adjacent segmental sections and being also provided with a plurality of perforations.

2. A false bottom for wash tubs and the like, including a removable bottom plate subdivided into segmental sections which all radiate from a common center, each of the segmental sections being formed with a plurality of corrugations which are parallel to each other and to the radius passing through the middle of the segmental section, slots being formed in the valleys of the corrugations which extend substantially the full length thereof, while the crowns of the corrugations are each provided with a series of perforations.

In testimony whereof I affix my signature in presence of two witnesses.

RUDOLPH F. KLOPP.
